AIRCRAFT

Wieslaw Zenon Stepniewski, Springfield, Pa., assignor to
Boeing Airplane Company, Seattle, Wash., a corpora-
tion of Delaware

Filed Oct. 18, 1960, Ser. No. 62,636

Term of patent 14 years

(Cl. D71—1)

FIG. 1 is a front elevational view of an aircraft, showing my new design;

FIG. 2 is a top plan view thereof; and

FIG. 3 is a side elevation thereof, the opposite side being a mirror image of this disclosed side.

The bottom of the aircraft is plain and substantially the same in appearance as the top, aside from the rotors and duct as indicated in FIGS. 1 and 3.

I claim:

The ornamental design for an aircraft, substantially as shown and described.
